UNITED STATES PATENT OFFICE.

JUDSON L. MCKELLAR, OF BROOKLYN, NEW YORK, ASSIGNOR TO GASAU-THOMPSON COMPANY, INC., OF BROOKLYN, NEW YORK, A CORPORATION OF NEW YORK.

BEDSTEAD.

1,259,254.

Specification of Letters Patent. Patented Mar. 12, 1918.

Application filed February 2, 1916. Serial No. 75,672.

To all whom it may concern:

Be it known that I, JUDSON L. MCKELLAR, a citizen of the United States, and a resident of Brooklyn, in the county of Kings and 5 State of New York, have invented certain new and useful Improvements in Bedsteads, of which the following is a specification.

The invention pertains more particularly to couch beds and comprises, with the other 10 features of a bed of this character, a novel head section adapted to be supported in inclined position and to constitute a continuation of the bed frame. The spring of the bed will preferably be of the well known 15 "Diamond" fabric and will be continuous from the foot of the bed to the outer end of the head section, there being no break in the fabric at the adjoining portions of the body of the bed and said section, thereby rendering 20 the bed comfortable in use and convenient of manufacture.

The invention will be fully understood from the detailed description hereinafter presented, reference being had to the accompanying drawings, in which:

Figure 1 is a side elevation of a couch bed embodying my invention, the head section being shown by solid lines in an inclined adjustment and by dotted lines in its normal 30 horizontal position;

Fig. 2 is a top view, partly broken away, of the same, the head section being shown in its horizontal position;

Fig. 3 is an end view, on a larger scale, of 35 the bed, with the head section shown in its inclined position, and

Fig. 4 is a horizontal section through a portion of the bed, taken on the dotted line 4-4 of Fig. 3.

In the drawings, 10 designates the side rails of the main body portion of the bed, 11 the foot rail, and 12 the main supporting legs of the bed, said rails 10, 11 preferably being of angle iron formation and the upper ends of said legs being preferably riveted to the vertical flanges of the rails 10. The side rails 10 support the spring fabric 13 and are themselves connected by transverse rods 14, 15, which bow downwardly 45 suitably below the fabric 13 and at their ends are riveted to the horizontal flanges of the rails 10. The rod 15 is closely adjacent to the inner ends of the rails 10 and also to the inner ends of the side rails 16 for the 50 head section 17, the ends of said rod 15 thus

being at the joint between the body portion of the bed and the head section 17, in which location the rod 15 is of considerable value in not only connecting the side rails 10 but in imparting strength to the bed at the 60 point where the head section joins the body portion thereof. The side rails 10 extend outwardly beyond the inner edge of the head section 17, as at 18, and the legs at the head of the bed are riveted to the sections 18 of 65 the rails 10. The sections 18 of the side rails afford supports for the head section 17 when the latter is in its horizontal position, as shown in Fig. 1.

The head section 17 comprises the side 70 rails 16 and an outer end rail 19, and the spring fabric 13 extends continuously from adjacent to the foot rail 11 to the rail 19. The side rails 16 are pivotally secured, as at 20, to the vertical flanges of the side rails 10 75 in line with the ends of the bar 15, and the horizontal flanges of the side rails 16 are cut away, as at 21, for the purpose of permitting the head section 17 to be turned downwardly upon the rivets 20 into close alinement with 80 the horizontal flanges of the rails 10 and at the points where said flanges of the rails 10 are partly cut away to form the extending sections 18 of said rails 10, as indicated in Fig. 2. The side rails 16 and end rail 19 of 85 the head section 17 may be made in one continuous piece of angle iron.

The side rails 16 of the head section 17 have pivotally secured to them, as at 22, the upper ends of toothed bars 23, which are 90 connected together so as to have simultaneous movement by a bar 24 (Fig. 3). The lower ends of the bars 23 are deflected at an angle to the body portion of said bars and such deflected portions of the bars 23 95 are provided in their lower edge with teeth 25 adapted to engage upon the upper edge of an angle iron bar 26, which extends transversely between and is secured at its ends to the head legs 12. The ends of the bar 100 26 are riveted to the head legs 12 and in addition are further secured thereto and strengthened by means of brace bars 27 (Fig. 3) secured to said bar 26 and to said legs 12. The upper portions of the head legs 105 12 are bent inwardly and at their upper ends are secured to the outer ends of the side rails 10; and the lower portions of said head legs are vertical. The bar 26 is secured to the head legs 12 just below the in- 110

wardly bent portions of said legs, said bar thus being freely exposed to receive and co-operate with the toothed bars 23. The bar 26 and the lower portions of the head legs 5 12 stand outwardly from the vertical plane of the ends of the side rails 10, as shown in Fig. 1. The toothed bars 23 have their lower ends bent outwardly, as at 28, these outwardly bent portions serving as stops to prevent the bars 23 from being withdrawn 10 rearwardly from between the head legs 12.

When the head section 17 is in its horizontal position, the bars 23 project inwardly and rest upon the bar 26, as indicated by 15 dotted lines in Fig. 1, and when it is desired to incline the head section 17, said section is pulled upwardly and the bars 23 slide along the bar 26 and finally when the head section has reached its desired position 20 it will there be held by the engagement of the proper teeth of the bars 23 with said rod 26, as illustrated in Fig. 1 and also in Fig. 3. The head section 17 may be given various adjustments and in its several positions it will be very securely supported by 25 the bars 23 and bar 26.

The bed of my invention is durable, convenient of manufacture and comfortable in use.

30 What I claim as my invention and desire to secure by Letters-Patent, is:

1. A couch bed having a body portion comprising side rails, a foot end rail, foot supporting legs and head supporting legs 35 which are bent inwardly at their upper portions and secured to the head-ends of said side rails, a head section comprising side rails and end rail and pivotally secured to the side rails of the said body portion inwardly from the head supporting legs, a bar connecting the said head legs adjacent to the lower ends of the inwardly bent por-

tions of said legs, ratchet bars pivoted to opposite sides of said head section and connected together by a bar and adapted to engage the said bar which connects the head legs, and a transverse downwardly bowed rod connecting the side rails of said body portion at the place where the head section is pivoted thereto, the bed between the said rod and the said bar connecting said head-legs being entirely open.

2. A couch bed having a body portion comprising side rails, a foot end rail, foot supporting legs and head supporting legs 55 which are bent inwardly at their upper portions and secured to the head-ends of said side rails, a head section comprising side rails and end rail and pivotally secured to the side rails of the said body portion inwardly from the head supporting legs, a bar connecting the said head legs adjacent to the lower ends of the inwardly bent portions of said legs, and ratchet bars pivoted to opposite sides of said head section and connected together by a bar and adapted to engage the said bar which connects the head legs, said ratchet bars being deflected inwardly at their free portions and having their teeth in the lower edges of said portions and at the ends of said portions being bent laterally to form stops, and the bed between the upper portions of said head-legs above their said connecting bar and between the head-ends of the side rails of said body portion outwardly beyond the pivots of said head section being entirely open.

Signed at New York, in the county of New York and State of New York, this 17th day of January, A. D. 1916.

JUDSON L. MCKELLAR.
